UNITED STATES PATENT OFFICE.

CHARLES L. STURGES, OF CLAREMONT, CALIFORNIA.

ELECTORAL APPARATUS.

Application filed August 2, 1924. Serial No. 729,753.

My invention relates to and has for its purpose the provision of an electoral apparatus for collecting and counting votes and a ballot of prescribed form adapted for use in conjunction with the apparatus.

It is also a purpose of my invention to provide an electoral apparatus which meets the following requirements:

In general it shall permit a voter to use in full his electoral franchise as that is commonly given by civil governments.

(a) It shall permit the voter to vote for any person for any office that he shall have the right to vote for but none other.

(b) It shall, except at primary elections, permit the voter to vote a ticket made up of all candidates from one party, or in part of candidates from one party and in part of candidates of one or more other parties.

(c) It shall permit the voter to vote for as many persons for an office as he is lawfully entitled to vote for, but no more.

(d) It shall permit the voter to vote for or against any question that he may have a right to vote for, but none other.

(e) It shall provide for a segregation of all vote subjects, at a proclaimed election, such that they shall appear on the ballot sheet in two distinct classes, to wit: a class of subjects to whom, or which, votes are to be "registered," i. e., both recorded on a ballot sheet and counted; and another class, the votes to whom or which are recorded but not automatically counted.

Special effort has been made by me to make possible a tally of votes mechanically counted such that each voter may see the tally of his own votes without violating principles of secret balloting, and also may be lawfully cast at any proclaimed election and without facilities for registering, (i. e., both recording and mechanically counting) a goodly number of all votes cast.

(f) It shall reduce to the same minimum, as to the matter of recording a vote, the effort required to put the vote on record whether the vote be to a vote subject whose vote is to be mechanically counted, or not so counted.

Since before a political campaign takes place it is impossible to say how many vote subjects it may be necessary to enter on a ballot sheet, I have made it an object of my invention to provide a ballot form that may be conveniently expanded or contracted to meet the exigencies of succeeding elec-

tions of various scope. Furthermore, I have aimed to devise a form of enrollment for vote-subjects, such that there is provision made for voting on an indefinitely larger number of vote subjects than may be within the capacity of the counting machine to mechanically register.

It shall make it possible for two or more voters at the same time to be selecting the ticket they will vote, without its being necessary to have in one voting place as many vote counting machines as it may be necessary to have private booths in which to prepare tickets.

Furthermore, it is an object of my invention to provide an apparatus that may be conveniently altered to meet the requirements of succeeding elections.

I will describe only one form of apparatus embodying my invention, and will then point out the novel features thereof in claims.

In the accompanying drawings:

Figure 1 is a view showing in plan one form of counting mechanism embodying my invention;

Figure 2 is a vertical sectional view taken on the line 2—2 of Figure 1;

Figure 2^a is a diagrammatic view illustrating one arrangement of the counters employed in my abacus;

Figure 3 is a section of the forward end of the counting mechanism, showing the vote controller inserted therein;

Figure 4 is a side elevation, with parts broken away, of the counting mechanism in inspection position;

Figure 5 is a view similar to Figure 4, showing the counting mechanism in tripped position;

Figure 6 is a transverse section on the line 6—6 of Figure 2;

Figure 7 is a view showing in plan the vote controller inserted in the counting mechanism, parts being broken away; and

Figure 8 is a view of the obverse side of a preferred form of ballot sheet before folding.

Referring specifically to the drawings, in which similar reference characters indicate similar parts in the several views, my invention in its present embodiment comprises a base plate A which forms the top of a conventional ballot box B. Secured to the base plate A are end walls C to which is pivotally mounted a counting mechanism

designated generally at D. Supported for rocking movement on the end walls C is a tripping device E, which will be herein-after more fully described.

5 The counting mechanism D is pivotally mounted upon the end walls C by means of hinges 15^a, the hinge pins of which are removable to permit the counting mechanism to be removed and inverted after the 10 closing of the polls, in which position all of the balls or counters will be disposed in the channel 16 adjacent the transparent plate 20. In this position a photograph of the balls or counters can be taken to provide 15 a permanent record of their relative positions.

The counting mechanism D comprises a plurality of counting units 10, each of which contains an improved form of abacus, 20 which will be hereinafter more fully described. The counting units are of similar construction and are spaced apart by means of vertical partitions 11.

Extending through the partitions 11 and 25 side frames 12 are tie bolts 13, which are provided with heads 14 and nuts 15 engaging the outer surface of the side frames 12, this construction maintaining the counting units 10 in assembled relation and permitting the removal of any of the units or the 30 addition of further units to meet the requirements of an election.

Each of the counting units 10 is provided with an upper and lower ball channel 16 and 17, respectively, disposed in parallel relation and in communication with each 35 other at one end by a connecting ball channel 18 of semicircular form. Spacer blocks 19 form the confronting sides of the channels 16 and 17 and a transparent plate 20, preferably of glass, forms the opposite side of the upper channels 16 and is secured in position by metal strips 21 and 22 of angular form.

40 Transfer bars 23 form the lower side of the lower channels 17 and are supported for sliding movement upon pins 24 which are disposed in cut-out portions 25 adjacent the ends of the transfer bars 23. The cut-out portions are of a length that determines the reciprocal movement of the bars 23.

The transfer bars 23 are also provided with recesses 26 adjacent their forward ends and which are of a size sufficient to receive 45 only one at a time of the balls or counters a. Extending downwardly from the recesses 26 are vertical pockets 26^a of a diameter sufficient to receive only the totaling ball b. The recesses 26 and pockets 26^a are normally maintained in alinement with a vertical channel 27 by means of a coil spring 50 28.

I will now describe in detail the preferred 55 form of abacus embodied in each of the counting units 10, which includes the balls

or counters a (Figures 2 and 2^a), preferably twenty-four in number, and of quarter inch diameter, and the totaling counter b of smaller diameter than the counters a. To preserve secrecy in tallying a register of 70 votes, number symbols are eliminated from the counters. Thus it is made possible for each elector to see the count of his own votes, entering the totals that he would augment, and yet violate no principle of secret 75 balloting.

At the beginning of an election, the counters in all of the abaci are positioned as shown in Figure 2, the totaling counter b being disposed at the head end of the series 80 of counters a. After an actuation of a transfer bar 23 the leading counter a', which will be distinctively colored or marked, will be positioned immediately behind the totaling counter b. Each time the 85 transfer bar 23 is actuated, an additional counter is disposed behind the totaling counter b, until the latter leads the series, this position requiring twenty-four movements of a transfer bar. Upon the twenty- 90 fifth operation of the latter, the totaling counter b will drop into the pocket 26^a and the counter immediately following (which was previously the leading counter a' shown in Figure 2) will be disposed above and 95 within the recess 26, this operation serving to change the position of the totaling counter b with respect to the leading counter a' from its initial position to a position 100 between the counter a' and the next succeeding counter. It will be obvious that every twenty-fifth operation of a transfer bar results in a change in position of the totaling counter b with respect to the leading counter a', thus registering twenty-five votes. 105

As an example, and by reference to Figure 2^a, it will be seen that the totaling counter b has advanced a distance of five counters from and including the counter a', which movement has required 5×25 operations of the transfer bar, or 125 operations, to which must be added the number of counters following the totaling ball b or 15, giving a grand total of 140 votes cast for that particular vote subject in whose 115 service the vote counter abacus is used.

By reference to Figure 2, it will be seen that the leading counter a' as well as the 120 5th, 8th, 14th, 17th and 18th counters from and including the leading counter have been illustrated as being black in color, the object of which is to facilitate determining the position of the totaling counter b when it is desired to obtain the total number of votes cast for a particular candidate. It will be 125 clear that the black counters in no manner indicate to the voter the total number of votes cast because of the fact that they are delivered singly and the other counters concealed from view, thus making it impossible 130

for the voter to determine the number serially of any one of the black counters with respect to the other counters.

It will be noted that the lower channels 17 terminate short of the vertical channel 27 and that it is necessary to effect a rearward movement of the transfer bar 25 to transfer a ball from the lower channels 17 into either the recess 26 or the pocket 26^a. The channels 17 are inclined toward the vertical channel 27 so that the counters *a* will gravitate toward the latter.

A gate bar 29 is supported for reciprocating movement in a guideway 30 extending transversely with respect to the channels 16 and adjacent the forward end thereof. The gate bar 29 is of sufficient length to span all of the counting units 10 and has secured at its opposite ends vertical pins 31 slidable in the bores 32 provided in the side frames 12. Coil springs 33 maintain the gate bar 29 in closed position, as shown in Figure 2, thus preventing communication of the vertical channels 27 with the channels 16.

Pins 34 are secured to the rear ends of the transfer bars 23 and are provided with pointed ends, which latter are adapted to perforate a suitable ballot F which is in vertical position within a slot 35 cut in the base plate A. The ballot F repose upon a gate 36 slidably secured to the under side of the base plate A by means of a screw 37.

An operating rod 38 is secured to the gate 36 and extends through the eye of a screw 39 to a point without the ballot box B and terminates in a looped end 40. A spring 41 is connected to the gate 36 and normally maintains the latter in position to close the slot 35. After the ballot F has been perforated and it is desired to deposit the same in the ballot box, the rod 38 is pulled forwardly against the tension of the spring 41 to clear the slot 35 and allow the ballot F to gravitate into the ballot box.

To insure the perforation of the ballot F, I have provided an abutment plate 42, perforated in alinement with the pins 34. A stripper plate 43 which is secured to the side frames 12 of the counting units is also perforated to receive the pins 34 and insure the proper stripping of the ballot F therefrom.

The tripping device designated generally at E comprises a pair of standards 44 secured to the end walls C and having their upper ends bored to rotatably receive the ends of a trip bar 45. To one end of the latter is secured a hand lever 46, which normally occupies the position shown in Figure 2. Extending longitudinally of the trip bar 45 and secured thereto is a plate 47, which is adapted to support a checking strip to be described hereinafter.

I have illustrated in Figures 3 and 7 a preferred form of vote controller designated generally at V, and which is used in con-

junction with the counting mechanism D. The vote controller V comprises a rectangular plate 48 provided with spaced perforations 49 in which studs 50 are removably fitted and provided with transverse bores 51, 70 registering to slidably receive a rod 52.

Extending lengthwise along one edge of the plate 48 is a series of blocks 53 spaced apart a distance equal to that of the counting units 10 and between which fingers 54 75 pivoted upon the rod 52 are adapted to be received.

The plate 48 is provided with slots 55 adjacent its ends, which are adapted to receive vertical pins 56 fixed in the forward end of the end walls C, to insure proper longitudinal alinement of the vote controller with the counting units when the former is inserted in the latter. The pins 56 extend through slots 57 provided in the end walls C, which slots receive the ends of the plate 48 to insure proper vertical alinement of the vote controller with the counting mechanism, as clearly shown in Figures 3 and 7.

The voter may select the ticket he will vote from a list of vote subjects as they appear on the full ballot sheet, making no use whatever of the strip or abbreviated ballot hereinbefore referred to except as the strip is a part of the ballot sheet. In this case he adjusts his full ballot to the vote controller in such way that vote subjects on pages I and II aline with correspondingly numbered parts as formed on the vote controller and ballot sheet. Where the vote subject to be chosen is found on pages I and II, the voter indicates his choice by turning over to operative position the fingers that will actuate the counter doing service, as vote meter, to his favored candidate, thus making ready for the automatic recording and counting of a vote that will take place when the vote controller is adjusted to the counting machine, but, where the vote subject is to be chosen from a list of vote subjects, appearing on any other pages than the double page marked I and II, the voter will indicate his choice by recording a vote-mark in a square on a page beyond pages I and II. All such recorded votes must be canvassed and counted by the election board.

As a flexible shield 58, (Figure 3) preferably of canvas or similar material, is secured along one edge of the plate 48 by rivets 59. Secured to the shield 58 along its opposite edges is a rod 60, which has its end bent at right angles to form hooks 61 (Figure 7) which cooperate with hooks 62 fixed on the end walls C.

A metal shield 63 is fixed to, and extends across the forward end of the counting mechanism D and co-operates with the shield 58 to conceal the plates 48 when the vote controller is inserted in the counting mechanism. Handles 64 are secured at opposite

ends of the plate 48 and provide suitable grips for holding the vote controller and inserting the latter in the counting mechanism D.

5 I have shown in Figure 8 a plan of the preferred form of ballot F which is intended to be folded along the lines 65 in such a manner that the pages I and II will form the obverse and reverse sides of the ballot, 10 respectively. When the ballot F is thus folded, the strip portion 66 to the right of the broken line 67 projects beyond one edge of the ballot F and is positioned uppermost when the ballot F is placed in the voting machine as is shown in Figure 2.

15 The ballot F is divided horizontally into equal spaces 68, which latter correspond with the spacing of the counting units 10. In the strip portion 66 I provide vote squares 68^a 20 which, when the ballot is positioned in the voting machine, are aligned both vertically and horizontally with the perforating pins 34. Letters 68^a are alphabetically arranged opposite the vote squares 68^a and correspond 25 to similar characters upon the blocks 53 of the vote controller V.

These characters identify vote subjects whose names, party affiliations and other information required by law appear as candidate 30 date cards upon pages I and II, and whose votes are to be automatically counted.

35 The reverse sides of pages I and II (pages IV and III respectively) are intended respectively for vote subjects designated in script or in print, but whose votes are not to be automatically counted. The sheet 70 which comprises pages V and IV provides an additional sheet to which further sheets can be affixed to comply with election laws 40 requiring a ballot which can be expanded to indefinite width. The length of the ballot may be enlarged by lengthening the pages.

45 In operation, the vote controller illustrated in Figures 3 and 7 is delivered to the voter, with the fingers 54 in the position shown in dotted lines, and is carried by the voter to a conventional voting booth. Upon arrival in the voting booth, the voter may consult a checking strip (not shown) which has been 50 detached from a reference or sample ballot and is a duplicate of the strip portion 66 of the ballot F. The voter may have previously marked this strip by a cross or other mark in the vote spaces identifying the vote subjects of his choice. This strip is provided adjacent its ends with perforations which are adapted to receive the locating pins 72 fixed in the plate 48. In this position, the characters identifying the spaces 55 between the blocks 53 of the plate 48 are in alignment with similar characters upon the strip and it is only necessary for the voter to slide one of the fingers 54 along the rod 52 until aligned with a previously marked vote square of the strip, and then rotate the

55 fingers 54 about the rod 52 until seated in the space between adjacent blocks 53 as is shown in full lines in Figures 3 and 7. This operation is repeated until the fingers 54 have been aligned with every marked vote 70 square of the strip. The flexible shield 58 is then positioned to cover the plate 48 and thus conceal the fingers 54 from view.

75 The voter now delivers the vote controller V to an election officer who secures the shield 58 to the hooks 62 upon the end walls C, and then inserts the vote controller into the voting machine in such a manner that the slots 55 are aligned with the pins 56 as is shown in Figure 7. Continuous inward movement 80 of the vote controller results in a corresponding movement to those transfer bars 23 in alignment with the fingers 54, which is clearly illustrated in Figure 3. In this position the recesses 26 are disposed beneath the 85 first balls a' of the several series, which drop therein by gravity. The vote controller V is then withdrawn and the coil springs 28 return the actuated transfer bars 23 to the normal position shown in Figure 2, with 90 each of the recesses 26 containing a ball a' in any instance where a finger is used. The counting mechanism is now rotated to the position shown in Figure 4, allowing the counters contained in the recesses 26 to pass 95 through the channels 27 by gravity and come to rest upon the gate 36.

95 It is optional with the voter whether or not he shall have an opportunity to inspect the tally made by the vote counting machine as 100 his own ballot passes through the counting machine. In case he chooses to make the observation, before the registering takes place, he will go to the rear of the machine, grasp the handle 46 of the tripping device E and 105 swing the former to the position shown in Figure 4, thus disposing the plate 47 in the path of the counting mechanism. The plate 47 is provided with pins 73, the latter receiving the perforations in the checking strip previously used in conjunction with the vote controller. In this position the vote spaces of the checking strip are in alignment with the channels 27 and the voter can readily observe if a counter is aligned with each of the marked vote spaces, as he had 110 designed to vote in accordance therewith. Furthermore, he may see that there are not tallies in any instance where he had not set the fingers to receive a vote.

115 After comparison and upon being satisfied that the balls a' and the marked vote spaces are in aligned relation, the voter removes the checking strip from the pins 73. The election officer thereupon moves the counting mechanism out of engagement with the plate 47, which latter returns to the position shown in Figure 5 by virtue of the counter-balancing action of the handle 46, and then 120 swings the counting mechanism to the posi- 125

tion shown in Figure 5, wherein the pins 31 engage and are depressed by the trip bar 45, and against the tension of the coil springs 33, thus moving the gate bar 36 to 5 clear the channel 16 and permit the counters α' to drop by gravity and to be finally disposed in a position at the rear of the row of counters upon the return of the voting machine to the position shown in Figure 2.

10 In the event that the voter does not wish to vote for a candidate whose name appears upon pages I and II and whose vote, it will be remembered, is to be automatically counted, the fingers 54 of the vote controller 15 in this particular instance being allowed to remain in the non-actuating position as shown in dotted lines in Figure 7. The ballot F is suitably marked along the same horizontal line to select a candidate for the 20 same office, upon any of the remaining pages, and then delivered, folded, to the election officer, who places the ballot in position upon the gate 36. The vote controller V is then inserted in the counting mechanism D and 25 the same procedure as previously described is carried out in connection with a perforated ballot. It will of course be necessary that the vote upon this and similarly marked candidate cards are counted by an election 30 board.

I claim:

1. An electoral apparatus comprising vote counting mechanism including ballot sheet perforating means and counting means, and 35 a vote controller for simultaneously actuating the perforating means and the counting means.

2. An electoral apparatus comprising vote counting mechanism including ballot sheet perforating means and counting means, a ballot sheet having an index strip adapted 40 to be perforated by said perforating means, and a vote controller for actuating the perforating means and the counting means.

45 3. An electoral apparatus comprising vote counting mechanism including ballot sheet perforating means and counting means, a ballot sheet having an index strip adapted to be perforated by said perforating means, a vote controller for actuating the perforating means and the counting means, a ballot box for receiving the ballot sheets after perforating, and manually operable means by 50 which the ballot sheets are deposited in the ballot box.

60 4. An electoral apparatus comprising vote counting means, ballot sheet perforating means, and a vote controller for operating the counting means and simultaneously perforating a ballot sheet.

65 5. An electoral apparatus comprising vote counting mechanism including ballot sheet perforating means and abaci, and a vote controller for actuating the perforating means and the abaci.

6. In an electoral apparatus, vote counting mechanism comprising a plurality of counting units each including an abacus, and a transfer bar movable to singly release the elements comprised in the abacus, and a perforator on the bar. 70

7. In an electoral apparatus, a vote counting mechanism comprising a plurality of counting units, and a portable and removable vote controller having selective fingers 75 for actuating any desired counting units.

8. In an electoral apparatus, a vote counting mechanism comprising a plurality of counting units, each including a channel having an open end and a closed end, an abacus comprising a plurality of elements movable in the channel, a gate common to all of the channels for controlling the movement of the elements into the open end of the channel, said gate being normally closed, 80 a transfer bar having an element receiving recess, said bar being movable to occupy one extreme position in which the recess is in communication with the open end of the channel, and another extreme position in which the recess is in communication with the closed end of the channel, to allow an element to gravitate into the recess, means for urging the bar to the first extreme position, so that when the bar is forced to the second 85 extreme position and then released an element will be transferred to the open end of the channel, means for mounting all of the units so that they normally occupy an inclined position but are capable of being moved to a vertical position, and means for opening said gate when the units are in vertical position whereby those abacus elements transferred are permitted to move to a new position for registering the operation 90 of the transfer bar. 95

9. An electoral apparatus as embodied in claim 8, wherein each transfer bar is provided with ballot sheet perforating means 100 operable upon movement of the bar to the second extreme position.

10. An electoral apparatus as embodied in claim 8, wherein each transfer bar is provided with a pocket, and each abacus includes a totaling counter which is adapted 105 to be received in said pocket, transferred to the open end of the channel and deposited in a new position with respect to the other elements in the manner and for the purpose described. 115

11. In an electoral apparatus, a vote counting mechanism comprising a plurality of counting units, each including a channel having an open end and a closed end, an abacus comprising a plurality of elements 120 movable in the channel, a gate common to all of the channels for controlling the movement of the elements into the open end of the channel, said gate being normally closed, 125 a transfer bar having an element receiving 130

- 6 recess, said bar being movable to occupy one extreme position in which the recess is in communication with the open end of the channel, and another extreme position in which the recess is in communication with the closed end of the channel, to allow an element to gravitate into the recess, means for urging the bar to the first extreme position, so that when the bar is forced to the second extreme position and then released an element will be transferred to the open end of the channel, means for mounting all of the units so that they normally occupy an inclined position but are capable of being moved to a vertical position, means for opening said gate when the units are in vertical position, whereby those abacus elements transferred are permitted to move to a new position for registering the operation of the transfer bar, each of said perforating means operable upon movement of the bar to the second extreme position, and a vote controller having selective means for actuating the transfer bars.
25. 12. In an electoral apparatus, a vote counting mechanism comprising a plurality of abaci, and means for movably supporting the mechanism to effect a new order of the counters comprised in each abacus in the manner and for the purpose described.
30. 13. In an electoral apparatus, a vote controller comprising a plurality of fingers manually movable to occupy one extreme position in which they are adapted to be inactive to actuate transfer bars, and another extreme position in which they are adapted to be active to actuate the transfer bars when the controller is moved toward the bars.
35. 14. In an electoral apparatus, a vote controller comprising a frame adapted to be supported for sliding movement, and fingers pivoted on the frame to independently occupy projected or retracted positions with respect to the frame.
40. 15. An electoral apparatus comprising vote counting mechanism including a plurality of counting units, a controller having selective means by which predetermined counting units are operated, and ballot sheet perforating means operable by the counting units.
45. 16. In an electoral apparatus, vote counting mechanism comprising a plurality of counting units, each including an abacus, and means movable to singly release the elements comprised in the abacus, and a ballot perforating means operatively associated with said first means.
50. 17. An electoral apparatus comprising vote counting mechanism including a plurality of counting units, each unit including an abacus, said mechanism mounted for movement to occupy one extreme position in which certain of the elements comprised in the abaci are adapted to be transferred, a second position in which the elements transferred can be inspected, and a third position in which the transferred elements are released to occupy a new position with respect to the other elements of their respective abaci.
55. 18. An electoral apparatus comprising vote counting mechanism including a plurality of counting units, each unit including an abacus, said mechanism mounted for movement to occupy one extreme position in which certain of the elements comprised in the abaci are adapted to be transferred, an intermediate position in which the elements transferred can be inspected, a second extreme position in which the transferred elements are released to occupy a new position with respect to the other elements of their respective abaci, and means for limiting at will the movement of said mechanism to either of said intermediate or second extreme position.
60. 19. An electoral apparatus as embodied in claim 18 wherein said last means comprises a support, a trip member rotatably mounted upon the support and disposed in the path of movement of said mechanism, an extension secured on the trip member and rotatable therewith to occupy one position in the path of movement of the mechanism so as to limit the movement of the latter to said intermediate position, and another position out of the path of movement of the mechanism so as to permit movement of the latter to its second extreme position, wherein it is supported on the trip member.
65. 20. An electoral apparatus as embodied in claim 18 wherein said last means comprises a support, a trip member rotatably mounted upon the support and disposed in the path of movement of said mechanism, an extension secured on the trip member and rotatable therewith to occupy one position in the path of movement of the mechanism so as to limit the movement of the latter to said intermediate position, another position out of the path of movement of the mechanism so as to permit movement of the latter to its second extreme position, wherein it is supported on the trip member, a gate controlling the movement of the elements from the inspected position to the new position, and means for moving the gate to open position as the mechanism engaging the trip member.
70. 21. An electoral apparatus as embodied in claim 8 wherein said gate is provided with pins and said last means comprises a support, a trip bar on the support disposed in the path of movement of said pins so as to be engaged by the latter and thereby move the gate to open position.
75. 22. An electoral apparatus comprising vote counting mechanism including ballot sheet perforating means and counting means, a ballot sheet having a portion thereof adapt-
80. 85. 90. 95. 100. 105. 110. 115. 120. 125. 130.

BEST AVAILABLE COPY

ed to be perforated by said perforating means, and a vote controller for actuating the perforating means and the counting means.

5 23. An electoral apparatus comprising a support having means for supporting a ballot in position for perforating, vote counting mechanism including ballot sheet perforating means movable on the support to occupy

10 one position to permit application of the ballot to the support, and a second position in which its perforating means is brought into operative relation to the ballot so as to permit perforation of the latter.

15 24. An electoral apparatus as embodied in claim 23 wherein said support is provided with an opening communicating with the interior of a ballot box, and a gate is mounted upon the support to normally close said opening and support a ballot in upright position therein, said gate being manually movable to release said ballot and thereby permit the ballot to be deposited into the ballot box.

20 25. In an electoral apparatus of the char-

acter described, an abacus comprising a 25 series of counting elements and a totaling element, said elements adapted to occupy an initial position with the totaling element disposed at one end of the series, the counter at the opposite end of the series and intermediate groups of counters being distinctively colored or marked to facilitate determining the total represented by the counters when occupying other than said initial position.

26. An abacus as embodied in claim 25, 30 wherein certain of the series of counting elements are distinctly marked and arranged in groups with the counters of the groups increasing in number consecutively from one end of the series to the other.

27. An electoral apparatus comprising means for perforating ballot sheets to permanently designate thereon the vote subjects voted for, and means for simultaneously counting the votes thus designated for each 40 45 vote subject.

CHARLES L. STURGES.
